(57) **CLAIM**

The ornamental design for a vehicle door latch adaptor, as shown and described.

DESCRIPTION

FIG. 1 is a top-left perspective view of my new design for a vehicle door latch adaptor, configured for a driver’s side vehicle door latch;

FIG. 2 is a bottom-left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof.

FIG. 9 is a top-right perspective view of another embodiment of a vehicle door latch adaptor, configured for a passenger’s side vehicle door latch;

FIG. 10 is a bottom-left perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

FIG. 17 is a top-left perspective view of another embodiment of a vehicle door latch adaptor, configured for a driver’s side vehicle door latch;

FIG. 18 is a bottom-left perspective view thereof;

FIG. 19 is a front view thereof;

FIG. 20 is a rear view thereof;

FIG. 21 is a left side view thereof;

FIG. 22 is a right side view thereof;

FIG. 23 is a top view thereof; and

FIG. 24 is a bottom view thereof.

FIG. 25 is a top-right perspective view of another embodiment of a vehicle door latch adaptor, configured for a passenger’s side vehicle door latch;

FIG. 26 is a bottom-left perspective view thereof;

FIG. 27 is a front view thereof;

FIG. 28 is a rear view thereof;

FIG. 29 is a left side view thereof;

FIG. 30 is a right side view thereof;

(Continued)

FIG. 31 is a top view thereof; and, FIG. 32 is a bottom view thereof. The dashed broken lines shown in FIGS. 1, 9, 17 and 25 show environment only, and portions of the vehicle door latch adaptor that form no part of the claimed design. The dashed broken lines shown in FIGS. 2, 3, 10, 11, 18-23, and 26-3 show portions of the vehicle door latch adaptor that form no part of the claimed design.
